Attorney.

UNITED STATES PATENT OFFICE

2,054,059

HOSIERY

William J. Longtin, Reading, Pa., assignor to
Infant Socks Company, Reading, Pa., a corpo-
ration of Delaware

Original application July 19, 1934, Serial No.
736,087. Divided and this application April
23, 1936, Serial No. 75,998

19 Claims. (Cl. 66—172)

This application is a division of application
Serial Number 736,087 filed July 19, 1934.

In the drawing:

Fig. 1 is a section in enlarged detail of a tubu-
lar rib wrap design top having an inlaid rubber
or elastic yarn garter.

Fig. 2 is a view of a stocking or anklet showing
the general location of the garters, the rib top
being unfolded and

10 Fig. 3 is a similar view with the top folded to
wearing normal position.

In the manufacture of tubular rib wrap tops
of the type shown, by way of example, in Larkin
15 Patent 1,772,400 and made upon the Larkin ma-
chine Patent 1,841,249, a wrap design thread
and a finger for the same is provided for each
cylinder needle, the design depending upon the
wrapping or the non-wrapping of the design
20 thread by the finger around the associated
needle. In providing an inlay elastic thread,
which may be of the type known commercially
as Lastex or of any other type, to act as a
garter in the completed article, there must be no
25 interference between the design threads and the
elastic yarn in the article and no interference
between the operation of the fingers and the
elastic yarn inlay mechanism in the machine.

From the preceding paragraph it will be ob-
vious that the problem solved by my invention
30 relates to wrap design threads as incorporated
into fabric formed by the needles, the design
threads being of the type known as wrap
threads. In the Larkin patents the wrap threads
are associated with the cylinder needles, al-
35 though the machine makes rib fabric. If the rib
needles were omitted the same problem of as-
sociating the elastic thread with the wrap
threads and the fabric formed by the cylinder
needles would still be present and the machine
40 would knit plain fabric. In the Larkin patents
the wrap threads are of the type that extend
vertically in a single wale. However it will be
obvious that my invention is applicable to de-
sign threads which extend differently with re-
45 spect to the wales. For instance the design
threads may extend horizontally or may extend
horizontally for several wales in a course and
then extend vertically for the same or other
wales in an adjacent course. This type of wrap
50 design is shown in the patent to Lawson
1,702,608 in which a group of wrap threads each
are associated with a certain group of needles.
In Lawson a wrap thread may form a design
upon the ground fabric by knitting in plating
55 relation to the ground fabric at a selected needle

or needles in a course and also at other selected
needle or needles in the same course, the inter-
vening needle or needles knitting the ground
fabric only, the wrap thread extending as a
float along the course between the points at 5
which it is knitted and extending vertically from
course to course.

My invention is applicable to all types of wrap
design fabric whether of the single wale wrap of
Larkin, the multiple wale wrap of Lawson or 10
any other type of true or mock wrap design
fabrics. Mock wrap designs are made by what
is known as float thread plating.

A further object of my invention in the use
of elastic yarn in patterned tubular stocking 15
fabric in addition to the garter effect created
by the use of the elastic yarn is to draw the
patterned wales into close proximity with each
other. In rib fabric the dial wales intervene be-
tween the plain or cylinder wales and to a cer- 20
tain extent are visible between the plain wales.
Therefore when selected stitches of the plain
wales are ornamented by the design stitches, the
pattern effect created by the designs upon the
selected stitches in the plain wales is often 25
marred by the visible intervening dial wales.
However with the use of the tensioned elastic
yarn these plain wales are brought into very
close proximity with each other, so that they
practically are in physical contact, thus cre- 30
ating a unitary pattern effect of the selected de-
sign stitches in the nonadjacent plain wales.
It will be understood that the rib fabric or its
equivalent is necessary for a stocking top, as it
allows for expansion and contraction, qualities 35
deemed necessary for the stocking top. In other
types of fabrics such as plain, not rib, which are
used to simulate the appearance of and act as
the equivalent in physical properties of rib fab-
ric, that fabric must also be capable of contrac- 40
tion and expansion in order to perform the same
functions as rib fabric in a stocking top. These
plain fabrics in order to have these qualities are
made with certain spaced recurrent plain wales
extending or held forwardly and the intervening 45
spaced recurrent plain wales extending or held
rearwardly. This initial positioning of the plain
wales in plain fabric is intended to simulate the
rib fabric and to provide a physical structure
which will allow for the fabric expansion neces- 50
sary to a stocking top. One way of holding the
plain wales in this relationship to each other is
by means of tensioned elastic thread as shown
in the British patent to Sturgess et al. Number
4,418 of 1886. The elastic thread provides the 55

contractile quality. It will also be apparent with the use of my invention that in the plain fabric simulating rib fabric that such plain fabrics may be ornamented to give a unitary design effect by 5 ornamenting selected stitches with additional threads or otherwise, in the spaced nonadjacent forwardly extending plain wales and that the close proximity of these wales will create this effect.

10 The mechanism whereby the combination of rib wrap tops or fabric and elastic yarn garter inlay may be made is shown in application Serial Number 736,088 filed July 19, 1934. As clearly shown in said application the elastic 15 yarn is placed in the fabric under a certain amount of tension.

The wrap design elastic yarn garter inlay tubular rib tops may be used on infants' socks or hosiery or upon full length socks or hosiery. 20 It may be used at any place where tubular rib fabric may have a function such as in sweaters, etc.

In Fig. 2 an infant's sock is shown having the plain foot 1 and the rib top 2 joined to the foot 25 1 at 3 in the usual manner. At 4, 5 and 6 are shown elastic yarn inlays of a number of courses, here shown as three, which depending upon the strength of the garter desired, may be of any suitable number of one or more courses. The 30 garter inlays may be placed wherever desired, that is only at 4, 5 or 6 or at any combination of these or other places. The rib top 2 is of the folding over type, folding on line 7 to provide the top as shown in Fig. 3 having the wrap design 35 indicated at 8 on the outer face. The folded over top conceals the inlays 5 and 6, and while the inlay 4 is shown diagrammatically in Fig. 3 as being as prominent as inlays 5 and 6, actually the wrap design threads aid in concealing the 40 inlay from view. The inlays 5 and 6 are not themselves prominent due to the coverage by the outside wales and the design threads makes the inlay 4 even less prominent.

In the straight or unfolded type of rib top, 45 the wrap design will appear as usual on the outside face and the inlays may be either below or above or at the design.

In Fig. 1 is shown a diagrammatic detail of the rib top having outside rib wales 9, 10, 11, and 50 12 and inside rib wales 13, 14, 15, and 16 of body yarn 17. The body yarn may be changed for horizontal striping as in said Larkin Patent 1,772,400. The wrap design threads of the single wale type are shown in course 18 at wales 9, 11, 55 12 at 23, 24, and 25. At certain courses the wrap threads are plated on the body stitches, as for example in course 18 at wale 9, and in other courses the wrap threads are floated in back of the body stitches, as for example in course 19 at 60 wale 9. This is well known as disclosed in the said Larkin patent. When other types of extra design thread fabrics are used the floats will vary with each such type of fabric.

The elastic thread inlay is shown at 26 extending horizontally between the outside and inside rib wales and being substantially hidden thereby. The beginning end portion of the elastic thread is securely anchored by means of interknitting as single or unplated stitches 27 and 70 28 with the adjacent outside body yarn stitches of courses 18 and 19 in wales 10 and 11. Likewise the end portion of the rubber or elastic thread is anchored by stitches 29 and 30 between the courses 21 and 22 of the body yarn in wales 75 10 and 11. It is obvious that the elastic thread

stitches may be in more than two wales if desired, to give additional security in anchoring the ends. It is also obvious that the end portions of the elastic thread may be anchored in other ways, for example the stitches 27 and 28 and 29 5 and 30, instead of being single yarn stitches interknitted between body yarn stitches in the wales 10 and 11, may be plated over the appropriate body yarn stitches in which case the body and the elastic threads are knitted together. 10

Other ways in which the elastic thread may be incorporated in the base fabric in addition to the design threads are shown in the British patent to Sturgess et al. Number 4,418 of 1886, and 15 in Lawson 1,843,086. In Sturgess the elastic thread is fed to the needles so that it falls below the opened latches of the needles and is cast off unknit when the main yarn is knitted. In Sturgess the elastic thread is so fed to spaced 20 apart needles and passes to the rear of in between needles. The elastic thread may also be incorporated by feeding the same to spaced apart needles to be knitted by those needles, instead of being cast off unknit as in Sturgess. 25 This means that the needles taking the elastic thread do so in their hooks or certainly on their latches. The in between needles do not take the thread which passes to the rear of the same.

It will be obvious that the elastic thread may 30 be incorporated in the base fabric, whether rib or plain, in many ways and that the base fabric may be ornamented by many types of wrap or design forming threads and I have combined these in the same fabric without interference 35 with each other or with the base fabric. It will also be obvious that by means of the tensioned elastic yarn that the spaced design wales are brought into close proximity with each other to give a unitary design effect.

In wales 9, 11, and 12 it will be seen that the 40 wrap threads extend in back of the elastic inlays, both when floating in unknitted relation to the body stitches and also when passing from one body stitch to an adjacent one in plated relation thereto, as particularly shown in wale 12. This binds the elastic inlay securely between the wrap thread and the outside rib wales.

In Fig. 1 is shown the relation of the elastic inlay to the rib stitches and to the wrap thread 50 stitches in a design portion of the rib top such as at 4. At both 5 and 6, where the wrap designs are absent, the relation of the elastic inlay to the rib stitches is similar to that shown in Fig. 1, and with the exception of the absence of the wrap 55 threads, is in all other respects identical therewith.

It will also be apparent that I have provided a novel method of anchoring elastic inlaid thread so as to prevent the same from creeping along 60 the courses, I refer to the extra single yarn stitches of elastic thread.

I claim:

1. A tubular stocking having a top of weft ground fabric comprising wales and courses, the 65 combination therewith of design threads forming wrap designs on said ground fabric at selected stitches of alternate wales and an elastic thread under tension incorporated unknit in said ground fabric at the rear of said alternate wales, said 70 elastic thread drawing said alternate wales into close proximity with each other, said elastic thread also acting as a garter.

2. A tubular stocking having a top of weft ground fabric comprising wales and courses, the 75

- combination therewith of design threads forming wrap designs on said ground fabric at selected stitches of spaced wales and an elastic thread under tension incorporated unknit in said ground 5 fabric at the rear of said spaced wales, said elastic thread drawing said spaced wales into close proximity with each other, said elastic thread also acting as a garter.
3. A tubular fabric knitted of a weft ground 10 thread comprising wales and courses, the combination therewith of design threads forming wrap designs on the ground fabric at selected stitches of selected spaced wales in selected courses and an elastic thread under tension incorporated unknit for one or more courses in said 15 ground fabric, said elastic thread drawing said spaced wales into close proximity with each other.
4. A tubular stocking having a top of weft ground fabric comprising wales and courses knit 20 entirely of a ground thread or threads, the combination therewith of design threads forming knit designs on said ground fabric at selected stitches of selected spaced wales in selected courses and an elastic thread under tension incorporated in 25 the wales of the ground fabric, said elastic thread drawing said spaced wales into close proximity with each other.
5. A tubular stocking having a top of weft ground fabric comprising wales and courses knit 30 entirely of a ground thread or threads, the combination therewith of design threads forming designs knitted on said ground fabric at selected stitches of selected spaced wales in selected courses, the design threads passing to the rear 35 of the fabric as floats between said selected stitches, and an elastic thread under tension incorporated coursewise in the wales of the ground fabric, said elastic thread drawing said spaced wales into close proximity with each other.
- 40 6. A tubular stocking having a top of weft ground fabric comprising wales and courses knit entirely of a ground thread or threads, the combination therewith of design threads forming wrap designs on said ground fabric at selected 45 stitches of selected spaced wales in selected courses, and an elastic thread under tension incorporated coursewise in the wales of the ground fabric, said elastic thread drawing said spaced wales into close proximity with each other.
- 50 7. A tubular stocking having a top of weft ground fabric comprising wales and courses knit entirely of a ground thread or threads, the combination therewith of design threads forming designs knitted on said ground fabric at selected 55 stitches of spaced apart wales, the design threads passing to the rear of the fabric as floats between said selected stitches and an elastic thread incorporated coursewise in the wales of the ground fabric, said elastic thread passing behind 60 said spaced wales and drawing the same into close proximity with each other.
8. A tubular stocking having a rib top comprising outside and inside rib wales, the combination therewith of wale threads forming wrap designs on said outside wales and an elastic inlay 65 extending between the rib wales for one or more courses, said elastic thread being under tension and drawing said outside wales into close proximity with each other.
- 70 9. A tubular stocking having a rib top comprising outside and inside rib wales, the combination therewith of wale threads forming wrap designs on said outside wales and an elastic thread inlay extending between the rib wales for one 75 or more courses, an end portion of the elastic
- thread being anchored in the rib top, said elastic thread being under tension and drawing said outside wales into close proximity with each other.
10. A tubular stocking having a rib top comprising outside and inside rib wales, the combination therewith of wale threads forming wrap designs on said outside wales and an elastic thread inlay extending between the rib wales for one or more courses, an end portion of the elastic 10 thread being interknit with the rib top, said elastic thread being under tension and drawing said outside wales into close proximity with each other.
11. A tubular stocking having a rib top comprising outside and inside rib wales, the combination therewith of wale threads forming wrap designs on said outside wales and an elastic thread extending between the rib wales for one or more courses, the end portions of the elastic 15 thread being interknit as single yarn stitches with the body stitches.
12. A tubular stocking having a rib top comprising outside and inside rib wales, the combination therewith of wale threads forming wrap designs on said outside wales and an elastic thread 20 extending between the rib wales for one or more courses, the end portions of the elastic thread being interknit with the body stitches by means of single yarn stitches.
13. A tubular stocking having a rib top comprising outside and inside rib wales, the combination therewith of wale threads forming wrap designs on said outside wales for a plurality of 25 courses and an elastic thread inlay extending between the rib wales in one or more of said courses, said elastic thread being under tension and drawing said outside wales into close proximity with each other.
14. A tubular rib top comprising outside and 30 inside rib wales, the combination therewith of wale threads forming wrap designs on said outside wales for a plurality of courses and an elastic thread inlay incorporated between the wales in one or more of said courses, said elastic thread being under tension 35 and drawing said outside wales into close proximity with each other.
15. A tubular stocking having a rib top comprising outside and inside rib wales, the combination therewith of wale threads forming wrap designs on said outside wales for several courses 40 and an elastic thread inlay incorporated between the wales in one or more of said courses, the floated portions of said wale threads extending in back of said elastic thread, said elastic thread 45 being under tension and drawing said outside wales into close proximity with each other.
16. A tubular stocking having a rib top comprising outside rib and inside plain wales, the combination therewith of wale threads forming wrap designs on said outside wales for a plurality 50 of courses and an elastic thread inlay incorporated between the wales in one or more of said courses, an end of said elastic thread being anchored in the rib top, said elastic thread being 55 under tension and drawing said outside wales into close proximity with each other.
17. A tubular stocking having a top of weft ground fabric comprising wales and courses knit entirely of a ground thread or threads, the combination therewith of design threads forming 60 wrap designs on said ground fabric at selected stitches of selected spaced wales in selected courses, and an elastic thread under tension incorporated coursewise in the wales of said ground 65

- fabric, an end of said elastic thread being anchored in the ground fabric, said elastic thread drawing said spaced wales into close proximity with each other.
- 5 18. A tubular stocking having a top of weft knitted ground fabric comprising wales and courses, the combination therewith of design threads forming wrap designs on said ground fabric at selected stitches of selected courses in selected nonadjacent wales and an elastic thread under tension incorporated unknit for one or more courses in said ground fabric, said elastic thread drawing the said nonadjacent wales into close proximity with each other to form a unitary
- 10 pattern effect of the selected wrap stitches on the said nonadjacent wales, the said elastic thread also acting as a garter.
19. A tubular stocking having a top of weft knitted ground fabric comprising wales and courses, the combination therewith of an elastic thread under tension incorporated unknit for one or more courses in said ground fabric, said elastic thread drawing nonadjacent wales into close proximity with each other and wale threads forming 10 wrap designs on said ground fabric at selected stitches of selected courses in selected non-adjacent wales.

WILLIAM J. LONGTIN.
